UNITED STATES PATENT OFFICE.

JOHN I. BELLAMY, OF BROOKFIELD, AND JOHN E. GARDNER, OF CHICAGO, ILLINOIS,
ASSIGNORS, BY MESNE ASSIGNMENTS, TO AUTOMATIC ELECTRIC INC., OF CHICAGO,
ILLINOIS, A CORPORATION OF DELAWARE.

AUTOMATIC TELEPHONE SYSTEM.

Application filed August 25, 1923, Serial No. 659,304. Renewed June 20, 1927.

The present invention relates to automatic telephone systems in general, but is concerned more particularly with "directors", which as is known in the art are used to register, translate and retransmit telephone numbers in a multi-office telephone system; and the principal object, briefly stated, is the production of a new and improved director which is capable of being used in a telephone system in which the numbers differ as to the number of digits contained.

Reference will now be had to the co-pending application of Nelson, Serial No. 573,175, filed July 6, 1922, on which the present case 15 may be considered an improvement. In this prior case the directors are designed to receive two office digits and then to receive a subscriber's number consisting of a fixed number of digits. The number of digits may 20 vary between the different offices, but for any one office the number of digits in the subscriber's number must always be the same for the reason that if a number is assigned which contains a smaller number of digits 25 than the other numbers, the director does not "switch through" and free itself when the number is completed but waits for one or more other digits to be dialled, there being no means provided to cause the director to 30 switch through when the sending mechanism catches up with the registering mechanism. It is, accordingly, one object of the present invention to provide new and improved arrangements whereby a director switches 35 through as soon as it sends out all the digits in the subscriber's number which have been stored up.

It is a further object of the invention to 40 provide novel circuit arrangements whereby the switching through operation is accomplished without any possibility of any impulses being mutilated or lost in case the calling subscriber has not yet finished dialling the number and starts to dial about the time 45 the director starts to switch through.

Another object of the present invention is 50 the provision of new and improved circuit arrangements for maintaining the test potential on the test conductor of the director after the director has been freed, and until 55 the various switches in the director have been restored to normal position.

Still another object is to produce a director

in which the circuits are greatly simplified in order to render the operation more positive 55 and less susceptible to error.

There are various other objects, having to do mainly with the various circuit details connected with the carrying out of the main objects of the invention, which will not be mentioned here but will appear fully herein-after as the specification is further perused.

In addition to the co-pending application of Nelson referred to hereinbefore, this application may be considered as an improvement on or a modification of the following prior, pending U. S. applications: Nelson et al., S. N. 538,551, filed Feb. 23, 1922; Richardson et al., S. N. 547,866, filed March 29, 1922; Gillings, S. N. 598,239, filed Nov. 1, 70 1922.

Referring now to the accompanying drawings, comprising Figs. 1-5, inclusive, they show a sufficient amount of apparatus in a system embodying the principles of the invention to enable the invention to be thoroughly understood and its utility appreciated. None of the automatic numerical trunking switches are shown in the drawings, as these are old and well known, and the drawings are confined to only so much of the equipment as is necessary for an understanding of the invention.

Fig. 1 shows the calling substation A, of which the line terminates at the exchange in the line switch C. The line switch C has access to a number of repeaters of which the repeater R is one. This repeater has associated with it a first selector, as is indicated on the drawing, and also a secondary switch SS, which latter has access to a number of directors, of which the one shown in Figs. 2-5, inclusive, is one.

The portion of the director shown in Fig. 2 comprises the sequence switch S, whose 95 chief function is to switch the control lead from one to the other of the various operating magnets of the director. This drawing shows, also, the sequence switch S', whose chief function is to ground, one after the other, the various stop conductors associated therewith.

The portion of the director shown in Fig. 3 comprises the group of relays shown, and the associated sending switch SEN. The 100 105 function of the sending switch is to count off

the impulses as they are being sent out to operate the automatic switches, and to terminate the impulses of each digit when enough have been produced.

- 5 The portion of the director shown in Fig. 4 comprises the office register OR, and the intermediate distributing frame IDF. The function of the office register OR is to record 10 the two office digits of the desired number in preparation for their being translated into the correct digits and the correct number of digits to trunk the call to the desired office.

The remaining portion of the director shown in Fig. 5 comprises the four digit registers DR¹-DR⁴, inclusive, whose function is to register the digits of the subscriber's number as they are received, and also to control the switching through of the director when the sending mechanism catches up with 20 the registering mechanism.

The substation A, Fig. 1, has the usual and well known pieces of apparatus, including the calling device CD, which is used to control the register switches of the director, and 25 also to control the automatic switches in case the director catches up and switches through before the subscriber has finished dialling his number.

The line switch C in which the line of substation A terminates, is mechanically of the well known rotary type in which the wipers have no normal position and move in a forward direction only. The secondary switch SS associated with the repeater R, is mechanically 35 identical with the line switch C.

The sequence switch S, Fig. 2, is mechanically a simple switch having two wipers 106 and 107, which are operated in a forward direction only by the stepping magnet 103, and 40 which are released and restored to normal by the release magnet 104. The digit registers DR¹-DR⁴, inclusive, are of the same type of switch as the sequence switch S.

The sequence switch S' is a simple switch 45 comprising the wipers 110 and 111, which are driven in a forward direction only by the stepping magnet 108, and which are advanced upon the deenergization of stepping magnet 108 rather than upon the energization. The sending switch SEN, Fig. 3, is of the same type as the sequence switch S'.

The office register OR is a vertical and 50 rotary switch, and accordingly its bank contacts are arranged in horizontal rows or levels. This switch is operated in a vertical movement by its vertical magnet 307, and in a rotary movement by its rotary magnet 306, while it is released by the release magnet 308.

The apparatus having been described more 60 or less in general, the detailed description of its operation will now be given. For this purpose, it will be assumed that the subscriber at substation A desires to call a subscriber whose number, by way of example, 65 will be assumed to be 98-7654. The first two

digits 9 and 8 of this number are usually listed in the directory as the first two letters of an exchange name, the calling device then being provided with letters in addition to the digits. However, since the invention is not particularly concerned with the method of listing the numbers or with the particular form of calling device used, no such assumption will be made in the present case.

When the subscriber at substation A removes his receiver, a circuit is closed over line conductors 11 and 12 for line relay 15 of the line switch C. Line relay 15 thereupon energizes and places ground on private normal conductors 13 at armature 19, thereby making the calling line busy immediately. The grounding of private normal conductor 13 also closes a circuit for switching relay 14 and stepping magnet 21 in series. As a further result of the energization of line relay 15, it connects test wiper 23 to the junction of switching relay 14 and stepping magnet 21. The further operation now depends upon whether the trunk upon which the wipers of the switch are standing is busy or idle. Assuming that it is busy, switching relay 14 is short circuited by the ground potential encountered on the busy test contact by test wiper 25, and the wipers are advanced step by step in search of an idle trunk by the buzzer-like action of stepping magnet 21 which 95 interrupts its own circuit, and which is operated from ground encountered on the busy test contacts by test wiper 23. This operation continues until an idle trunk is reached, 100 at which time switching relay 14 is no longer short circuited and energizes.

In the present case, however, instead of assuming that the trunk upon which the wipers are standing is busy, it will be assumed 105 that the trunk is idle, in which case the connecting up of the test wiper at armature 20 does not produce any particular result, and switching relay 14 energizes immediately in series with stepping magnet 21. Stepping 110 magnet 21, however, does not energize at this time on account of the high resistance of switching relay 14. Upon energizing, switching relay 14 disconnects test wiper 23 from the junction of its own winding and that of stepping magnet 21 at armature 17 and connects it to the grounded private normal conductor 13, thereby making the seized trunk busy immediately and preparing a holding circuit for itself which becomes effective after 115 the deenergization of line relay 15. Also, relay 14 disconnects at armatures 16 and 18 line conductors 11 and 12 from the winding of line relay 15 and ground and extends them by way of wipers 22 and 24, bank contacts 120 25 and 27, trunk conductors 28 and 30, and the repeating coil windings 31 and 32 to the upper and lower windings, respectively, of line relay 41 of the repeater R. Line relay 125 41 now energizes over the calling line and 130

closes at armature 45 a circuit for release relay 42. Release relay 42, upon energizing, places ground on release trunk conductor 29 at armature 47, thereby completing the holding circuit for switching relay 14 in the line switch C through test contact 26 and test wiper 23. This holding circuit, of course, is completed before the slow acting line relay 15 has had time to deenergize. As a still further result of the energization of release relay 42, it closes at armature 49 a circuit through armature 53 and its resting contact for switching relay 61 and stepping magnet 62 in series, and at armature 48 connects test wiper 68 to the junction of switching relay 61 and stepping magnet 62 through armature 52 and its resting contact. The secondary switch SS now operates in the same manner as the line switch C to select an idle trunk. Assuming that the trunk on which the wipers 67-69, inclusive, are standing is idle, the stepping magnet 62 does not operate at all and switching relay 61 energizes immediately; prepares a circuit for repeating relay 44 at armature 63; prepares the impulsing circuit at armature 66; and at armature 64 places a shunt around armature 54 and its working contact, thereby completing a bridge across the conductors 56 and 58 extending to the associated first selector. This bridge includes the right hand repeating coil windings 33 and 34 and armature 55 and its resting contact. As a further result of the energization of switching relay 61, it disconnects test wiper 68 from the junction of switching relay 61 and stepping magnet 62 and connects it to ground, thereby making the seized director busy.

In the director switch release relay 203 now energizes over the following circuit: from ground by way of the working contact of armature 65 of relay 61 of the secondary switch SS, Fig. 1, and said armature, test wiper 68, test contact 71, release trunk conductor 74, normally closed contacts controlled by armature 207, and relay 203 to battery. Relay 203, upon energizing, opens the various restoring circuits of the director at armatures 209-212, inclusive, and at armature 210 places ground on the bank of the sending switch SEN preparatory to the subsequent operation of the said sending switch.

The above operations have all taken place in response to the removal of the receiver at the sub-station A, and the circuits are now in readiness for the first office digit 9 to be transmitted. When the calling device CD is manipulated in accordance with the first office digit 9, a corresponding number of interruptions is produced in the circuit of line relay 41 of the repeater R, with the result that line relay 41 is deenergized nine times momentarily. Each time line relay 41 deenergizes it closes a circuit for the vertical magnet 307 of the office register OR, Fig. 4, as follows: from

ground by way of the resting contact of armature 46 of line relay 41 and said armature, working contact of armature 66 and said armature, wiper 69, bank contacts 72, impulse conductor 75, slow acting series relay 102, Fig. 2, 70 wiper 107 of the sequence switch S, conductor 121, and vertical magnet 307 to battery. By the operation of vertical magnet 307, the wipers 311-314, inclusive, of the office register OR, are raised step by step and come to rest opposite the ninth level of bank contacts. Relay 102 is energized in series with vertical magnet 307 upon the first impulse of current delivered to the latter, and being slow acting retains its armature 114 attracted throughout the entire series of impulses. Upon energizing, relay 102 closes a circuit for the associated slow acting relay 101, and relay 101, upon energizing, prepares a circuit for stepping magnet 103 of the sequence switch S at 80 armature 115.

At the end of the series of impulses delivered to vertical magnet 307 of the office register OR, series relay 102 deenergizes and completes at armature 114 the circuit of stepping magnet 103 of the sequence switch S, 90 also opening the circuit of slow acting relay 101. Stepping magnet 103 of the sequence switch S advances the wipers 106 and 107 into engagement with the second set of associated bank contacts. Slow acting relay 101 deenergizes after an interval and opens the circuit of stepping magnet 103 at armature 115.

When the calling subscriber manipulates his calling device CD in accordance with the second office digit 8 of the desired number, line relay 41 of the repeater R deenergizes eight times momentarily, and upon each deenergization sends an impulse of current over 105 the previously traced circuit to wiper 107 of the sequence switch S and thence by way of conductor 122 to rotary magnet 306 of the office register OR. Accordingly, rotary magnet 306 receives eight impulses of current and 110 steps the wipers 311-314, inclusive, into engagement with the eighth set of bank contacts 321-324, inclusive, in the ninth level.

The sequence switch S is advanced one step at the end of this digit in the previously 115 described manner, and wiper 106 places ground on start conductor 114, thereby starting the sending equipment into operation. Before the operation of the sending equipment is taken up, the description of the registration of the remaining digits in the desired 120 number will be completed.

The wiper 107 is now in engagement with its third bank contact, and, accordingly, when the calling subscriber manipulates his calling device in accordance with the first digit 7 in the number of the desired subscriber, seven impulses of current are delivered over the previously traced circuit to wiper 107, and thence by way of the third associated bank 125 contacts 321-324, inclusive, to the vertical magnet 307 of the office register OR. The wiper 107 deenergizes and the circuit for the vertical magnet 307 is opened, thereby deenergizing the line relay 41 of the repeater R, and the circuit for the stepping magnet 103 of the sequence switch S is opened, thereby deenergizing the stepping magnet 103 and 130 advancing the sequence switch S to the fourth level.

contact and conductor 131 to stepping magnet 401 of the first digit register DR¹. As a result, stepping magnet 401 is energized seven times, and steps the wiper 405 into engagement with the bank contact in which the seventh impulse stop conductor 247 terminates.

The wipers of the sequence switch S are again advanced one step upon the termination 10 of this digit, and when the second digit 6 is called, stepping magnet 402 of the second digit register DR² is operated over conductor 132 and steps the wiper 406 into engagement with the bank contact in which the sixth impulse stop conductor 246 terminates.

Similarly, the sequence switch S is again advanced one step at the end of the second digit 6, and when the third digit 5 in the desired number is called, stepping magnet 20 403 of the third digit register DR³ is operated over conductor 133 and steps wiper 407 into engagement with the bank contact in which the fifth impulse stop conductor 245 terminates.

25 The wipers of the sequence switch S are again advanced upon the termination of the third digit 5, and, accordingly, when the fourth and last digit 4 in the number of the desired subscriber is called, stepping magnet 30 404 of the fourth digit register DR⁴ receives four impulses of current over the operating circuit and through conductor 134, and steps the wiper 408 into engagement with the bank contact in which the fourth impulse stop conductor 294 terminates.

At the end of the transmission of the last named series of impulses, the wipers 106 and 107 of the sequence switch S are advanced into engagement with the seventh set of bank contacts, and wiper 107 engages a dead contact.

40 The operation of the sending equipment will now be taken up. It will be noted that the office register OR has four wipers, and that the set of bank contacts shown comprises 45 four bank contacts. This permits a maximum of four series of impulses to be sent out to effect the trunking of the call to the desired office. In order to trunk the present call through to the desired office, it is assumed 50 that it is necessary to transmit only two series of impulses, the first comprising three impulses, and the second comprising nine impulses. Accordingly, the first and second bank contacts 321 and 322 of the ninety-eighth set associated with the office register OR are 55 connected by means of the IDF jumpers 301 and 302 to the skip conductor 305, and the third bank contact 323 is connected by means of the jumper 303 to the third impulse stop conductor 243, while the fourth bank contact 60 204 is connected by means of the jumper 304 to the ninth impulse stop conductor 249.

65 It will be remembered that wiper 106 of the sequence switch S, upon being advanced into engagement with the third associated bank

contact at the termination of the setting of the office register OR, places ground on start conductor 114. Accordingly, sending relay 204, Fig. 3, commences to energize and deenergize under the control of interrupter 70 226. The ground potential, which is placed on start conductor 114, also extends by way of wiper 111 of the sequence switch S', the first associated bank contact, conductor 141, the first wiper 311 of the office register OR, bank 75 contact 321, jumper 301, skip conductor 305, interrupter contacts 109 and stepping magnet 108 of the sequence switch S' to battery. Stepping magnet 108, accordingly, energizes and interrupts its own circuit at contacts 109, 80 whereupon it deenergizes and advances the wipers 110 and 111 into engagement with the second set of bank contacts. When this occurs, the ground potential is extended by wiper 111 over conductor 142, the second wiper 85 312 of the office register OR, bank contact 322, and jumper 302 to the skip conductor 305. Stepping magnet 108 is accordingly energized, and again interrupts its own circuit at contacts 109, whereupon it deenergizes and advances the wipers 110 and 111 into engagement with the third set of bank contacts. The movement of the sequence switch S' is arrested at this point and the wipers 110 and 111 remain in their present position 90 for the time being.

Upon the first effective energization of sending relay 204 in response to the above mentioned grounding of start conductor 114, sending relay 203 closes a circuit for stepping 100 magnet 223 of the sending switch SEN at armature 214. Upon energizing, magnet 223 attracts its armature causing the pawl thereof to engage the next notch in the associated wiper driving ratchet wheel. Then, upon the 105 following deenergization of relay 204, the circuit of stepping magnet 223 is opened and it deenergizes, advancing the wipers 224 and 225 in a clockwise direction into engagement with the first set of bank contacts. Wiper 110 224 closes a circuit for pick-up relay 205, which becomes energized; prepares a locking circuit for stop relay 206 at armature 217; prepares the impulsive circuit at armature 216; and at armature 215 closes a circuit 115 from ground through armature 218 and its resting contact for stepping magnet 108 of the sequence switch S'. Stepping magnet 108 thereupon energizes and attracts its armature, causing the pawl thereof to engage another notch in the associated wiper driving ratchet wheel.

120 Relay 204 continues to energize and deenergize and the wipers 224 and 225 are advanced upon each of the deenergizations. 125 Also, since relay 205 is energized, each energization of relay 204 thereafter results in a circuit being closed for sending relay 44 of the repeater R as follows: from ground by way of the working contact of armature 216 130

and said armature, working contact of armature 213 and said armature, conductor 73, bank contact 70, wiper 67, armature 63 and its working contact, normally closed contacts controlled by armature 50, and repeating relay 44 to battery. Each time the above circuit is closed, repeating relay 44 energizes and opens the bridge across conductors 56 and 58 at armature 55.

10 The operation continues as described until wiper 225 arrives upon the bank contact in which the third step conductor 243 terminates, at which time three impulses of current have been delivered to repeating relay 44 of the repeater R, Fig. 1. When wiper 225 arrives upon the fourth associated bank contact, stop relay 206 is energized over the following circuit: from ground by way of the start conductor 114, Fig. 2, wiper 111 of the sequence switch S', the third associated bank contact, conductor 143, the third wiper 313 of the office register OR, bank contact 323, jumper 303, the third impulse stop conductor 243, wiper 225 of the sending switch SEN, Fig. 3, and stop relay 206 to battery. Stop relay 206 thereupon energizes; closes a locking circuit for itself at armature 220; disconnects sending relay 204 at armature 221 while it is still in a deenergized condition; 30 and at armature 218 opens the circuit of stepping magnet 108 of the sequence switch S', whereupon stepping magnet 108 deenergizes and advances the wipers 110 and 111 into engagement with the next set of bank contacts.

35 As a still further result of the energization of stop relay 206, it connects wiper 224 to stepping magnet 223 through interrupter contacts 222 at armature 219. Stepping magnet 223 thereupon energizes from the ground potential placed on the bank contacts of wiper 224 at armature 210 and its working contact and interrupts its own circuit at armature 222. The wipers 224 and 225 are, accordingly, advanced step by step by the buzzing-like action of stepping magnet 223 until wiper 224 passes off the last grounded bank contact. When wiper 224 passes off the last grounded contact, in addition to stopping the operation of stepping magnet 223, it opens the circuit of pick-up relay 205. Pick-up relay 205, however, is slow acting and does not fall back immediately.

As a result of the three interruptions produced in the bridge across conductors 56 and 58, the selector switch associated with the repeater R' is caused to raise its wipers opposite the third level and select an idle office selector.

In the director, pick-up relay 205 deenergizes after an interval and opens the circuit of stop relay 206 at armature 217, and after an interval slow acting stop relay 206 energizes and connects up sending relay 204 again. The interval of time required for relays 205 and 206 to fall back one after the

other is utilized by the first selector which has just been operated in effecting the change over from the directive vertical operation to the automatic trunk hunting operation and in selecting an idle trunk.

70 Relay 204 now starts to vibrate again under the control of interrupter 226, and as a result a second series of impulses is sent out over the outgoing control conductor 73 to repeating relay 44 of the repeater R. These 75 impulses are counted off in the above manner by the sending switch SEN, and when nine impulses have been sent, the wiper 225 of the sending switch SEN arrives upon the bank contact in which the ninth impulse stop conductor 249 terminates, thereby completing the following circuit: from ground by way of the stop conductor control wiper 111 of the sequence switch S', the fourth associated bank contact, conductor 144, the fourth wiper 314 of the office register OR, bank contact 324, IDF jumper 304, and thence by way of the ninth impulse stop conductor 249 to battery through wiper 225 of the sending switch SEN and stop relay 206. The energization of stop 90 relay 206 terminates the second series of impulses being delivered to the repeating relay 44 of the repeater R, and causes the sequence switch S' to advance its wipers into engagement with the next set of bank contacts. The 95 sending switch SEN is also advanced automatically to its normal position.

The first digit 7 in the subscriber's number, which is stored on the first digit register DR¹, Fig. 5, is next transmitted. The series of 100 seven impulses representing this digit are terminated upon stop relay 206 being energized over conductor 151 and through wiper 205 of the first digit register DR¹, which is standing on the bank contact associated with 105 the seventh impulse stop conductor 247.

The sequence switch S' is again automatically advanced and brings the stop conductor control wiper 111 into engagement with the second digit stop conductor 152, and as a result the second digit 6 in the desired subscriber's number, after having been sent out in a manner described, is terminated upon the arrival of wiper 225 of the sending switch SEN upon the bank contact in which the sixth impulse stop conductor 246 terminates. The circuit of stop relay 206 at this time includes conductor 152, wiper 406 of the second digit register DR², the seventh associated bank contact, and the sixth impulse stop conductor 246.

110 At the end of the transmission of this series of impulses, the wipers of the sequence switch S' are advanced into engagement with the next set of bank contacts in preparation for the sending out of the third digit 5 in the subscriber's number.

115 At the termination of the fifth impulse sent out in accordance with the third digit 5, wiper 225 of sending relay SEN comes into 120

130

engagement with the bank contact in which the fifth impulse stop conductor 245 terminates, thereby completing a circuit for stop relay 206 which includes the third digit stop conductor 153, wiper 407 of the third digit register DR³, the sixth associated bank contact, and the fifth impulse stop conductor 245.

The next and last digit 4 is now transmitted and is terminated on the energization of stop relay 206, which occurs in response to wiper 225 coming into engagement with the bank contact in which the fourth impulse stop conductor 241 terminates. The circuit of stop relay 206, at this time, includes the fourth digit stop conductor 154, wiper 408 of the fourth digit register DR⁴, the fifth associated bank contact, and the fourth impulse stop conductor 244.

When sequence switch S' is again advanced, as it is upon the above mentioned energization of stop relay 206, the grounded wiper 111 comes into engagement with the next bank contact, thereby placing ground on the incoming impulse conductor 75. This conductor is at this time disconnected in the director owing to the fact that wiper 107 of the sequence switch S is standing on a dead contact. The impulsing circuit, however, extends in the repeater R through armature 46 of line relay 41 and its working contact, to the winding of switching relay 43 through the normally closed contacts controlled by armature 51. Relay 43 accordingly energizes; locks itself to release trunk conductor 57 and opens its initial circuit at armature 51; places a shunt around armature 64 and its working contact of switching relay 61 at armature 54; removes repeating relay 44 from under control of the director and places it under the control of line relay 41 at armature 50; opens a point in the previously closed test circuit of the secondary switch SS at armature 52; and at armature 53 opens the circuit of switching relay 61. Switching relay 61 thereupon deenergizes and frees the director.

The connection has now been extended to the called line, and has been removed from the control of the director and placed under the direct control of the calling subscriber.

It will be noted that the deenergization of switching relay 61 results in the ground potential being removed from release trunk conductor 74 at armature 65. Conductor 74, however, remains grounded through a circuit which has been previously closed in the director switch. This circuit is as follows: from ground by way of the off normal contacts 310 of the office register OR, conductor 112, and the upper winding of relay 202, Fig. 3, to release trunk conductor 74. This ground potential maintains the director non-selectable to the various secondary switches, such as the secondary switch SS, until the various switches of the director have been restored to normal position as will now be

pointed out. The ground potential placed on conductor 74 through the upper winding of relay 202, in addition to maintaining the director busy, maintains release relay 203 energized. Accordingly, relay 202 energizes in series with relay 203, and at armature 208, which is adjusted to come into engagement with its working contact before armature

207 breaks away from its resting contact, places ground through its own lower winding, on the release conductor 113, thereby closing a circuit for release magnet 104 of the sequence switch S through off normal contacts 105, and similar circuits for the release magnets of the registers DR¹-DR⁴, inclusive, as well as a circuit through off normal contacts 309 for release magnet 308 of the office register OR. The operation of armature 208 accordingly results in a locking circuit being closed for relay 202. As a further result of the energization of relay 202, it disconnects relay 203 and places direct ground on release trunk conductor 74 at armature 207.

In response to being disconnected by relay 202, relay 203 deenergizes and at armatures 209 and 210 closes a restoring circuit for the sending switch SEN, which is effective in case the latter is not in its normal position and which is as follows: From ground by way of the lower winding of relay 202, resting contact of armature 210 and said armature, the bank of wiper 224, wiper 224, armature 209 and its resting contact, interrupter contacts 222 and stepping magnet 223 to battery. As a further result of the deenergization of release relay 203, it closes at armature 212 a restoring circuit for the sequence switch S', which includes conductors 115, the bank of wiper 210, wiper 210, and interrupter contacts 109. All the various restoring circuits, it will be noted, include the lower winding of relay 203. Accordingly, relay 203 is maintained energized and maintains conductor 74 grounded until the last switch has been restored to normal position, at which time relay 203 deenergizes and renders the director accessible again.

Regarding the established connection, this connection is released in the following manner when the subscriber at substation A replaces his receiver: Line relay 41 deenergizes and closes a circuit through armature 50 and its resting contact for repeating relay 44, which accordingly energizes and opens the bridge across conductors 56 and 58 at armature 55. Release relay 42 deenergizes after an interval and removes ground from release trunk conductor 29 at armature 47. Assuming that the release trunk conductor 57 is extended through the various selector switches to the connector switch which finally completed the connection to the called line, nothing further happens until the ground potential is removed from the said release

trunk conductor in response to the deenergization of the release relay of the said connector switch, which is brought about owing to the fact that the bridge across conductors 56 and 58 is open at armature 55 of repeating relay 44. In this case, when the ground potential is removed from conductor 57, switching relay 14 of the line switch C and switching relay 43 of the repeater R deenergize immediately. Relay 43, upon deenergizing, opens a further point in the bridge across conductors 56 and 58 at armature 54, and at armature 50 opens the circuit of repeating relay 44, which relay accordingly deenergizes. The various selectors included in the connection are released in response to the removal of ground from release trunk conductor 57.

To explain the alternative arrangement, it may be stated that ordinarily the release trunk conductor 57 is not extended beyond the originating office, and that inter-office trunks comprise only two conductors. In this case, the ground potential is removed from conductor 57 as soon as release relay 42 deenergizes, and the connection is released in the same way as pointed out above.

The operation of the director in switching through when it catches up with the calling subscriber before he has completed dialling the desired number will now be explained.

For this purpose it will be assumed that the calling subscriber is calling a number, and that he stops after calling the office digits and before calling the first digit in the subscriber's number. In that case, the first digit register DR¹ is not moved from its normal position, and when wiper 111 of the sequence switch S' is moved into engagement with the fourth associated bank contact upon the termination of the sending out of the last digit, ground is placed on the impulse conductor 75 over the following circuit: From ground by way of wiper 106 of the sequence switch S, conductor 114, wiper 111, the fifth associated bank contact, conductor 151, wiper 405 of the first digit register DR¹, the first associated bank contact, switching conductor 227, spring 228 of the key K and its lower contact, and armature 229 and its resting contact to impulse conductor 75. The placing of ground on conductor 75 at this time closes two circuits. One extends through series relay 102, Fig. 2, and wiper 107 to battery by way of conductor 131 and stepping magnet 401 of the first digit register DR¹. The other circuit is the previously traced one to battery through switching relay 43 of the repeater R. Armature 51 of switching relay 43 is very lightly adjusted and, accordingly, relay 43 energizes quickly and closes a locking circuit for itself at armature 51 and then pulls all the way up, thereby completing the switching operation in the hereinbefore described manner, leaving the repeating relay 44 under the direct control of line relay 41.

The connection is then completed when the subscriber finally dials the remaining digits in the number, owing to the fact that the interruptions produced in his line circuit are repeated through line relay 41 and repeating relay 44 in the bridge across conductors 56 and 58.

The closure of the circuit through series relay 102 and stepping magnet 401 which was mentioned in the preceding paragraph results in an incidental operation of the said relay and magnet. Magnet 401, upon operating, advances wiper 405 into engagement with the second associated bank contact, thereby removing ground from conductor 75. This does not affect the previously mentioned energization of switching relay 43, however, owing to the fact that the said relay 43 is able to close its local locking circuit very much quicker than the magnet 401 can operate its comparatively heavy armature and advance the wiper 405 out of engagement with its first contact. The energization and deenergization of series relay 102 which occurs at this time results in an impulse of current being delivered to magnet 103 of the sequence switch S in the usual manner. This is of no utility, however, and the various switches of the director are immediately released in the hereinbefore described manner.

Unless special arrangements are provided to prevent it, a subscriber might cause one or two impulses to be lost by starting to call the next digit in the number just before or at about the same time that the director starts to switch through. With the present arrangement, however, this cannot happen, as will now be explained. Assuming that the calling subscriber decides to call the next digit in the desired number just before or at about the same time that the director starts to switch through, line relay 41, upon deenergizing, disconnects switching relay 43 at armature 46 and places ground on the impulse circuit. In case line relay 41 falls back and disconnects relay 43 before the switching operation has proceeded far enough to result in armature 51 of relay 43 being brought into engagement with its associated contact, nothing further happens in the repeater at this time, and stepping magnet 401 of the digit register DR¹ is operated by the ground potential placed on the impulsing circuit by line relay 41, and steps the wiper 405 out of engagement with switching conductor 227, and in response to each of the remaining impulses in the series the wiper 405 is advanced another step in the usual manner. The point is, that if relay 43 does not energize and close a locking circuit for itself before armature 46 of relay 41 breaks away from its working contact in response to the first deenergization of the line relay 41, relay 43 cannot energize until the sequence switch wiper 111 is again advanced, owing to the fact that before arm-

ture 46 of line relay 41 is again attracted, the wiper 405 of the digit register DR¹ has been moved out of engagement with the associated bank contact in which switching conductor 227 terminates.

It will be noted that the repeated impulses are slightly held up while going to the repeater R, owing to the fact that repeating relay 44 is energized when line relay 41 is de-energized. This is done so that a sufficient time will elapse, after armature 46 breaks away from engagement with its working contact and before the circuit of relay 44 is closed to effect the repeating of an interruption, to bring armature 50 into engagement with its associated contact after armature 51 has been operated.

It may be pointed out that in case the director starts to switch through just before a calling subscriber starts to operate his calling device again, the switching through operation is effected as described hereinbefore, but the director is not yet freed and the interruptions are repeated ahead to relay 44 and simultaneously the first digit register DR¹, Fig. 5, is operated over the impulsing circuit. This does not cause any harm to result, however, owing to the fact that as soon as switching relay 43 is fully energized it opens the circuit of switching relay 61 at armature 53, whereupon switching relay 61 deenergizes and frees the director in the hereinbefore described manner.

It will be noted that the sequence switch S', Fig. 2, is advanced immediately following the termination of each series of impulses, and if special arrangements were not made the director would cause the connection to be switched through right away—that is if it has "caught up" with the calling subscriber—with the result that, if a calling subscriber should then start dialling, the series of impulses thereby produced would be repeated ahead before the selector last operated has had time to select an idle trunk. This difficulty is taken care of, however, by maintaining conductor 227 disconnected from the impulsing conductor 75 at armature 229 of stop relay 206, Fig. 3, as long as the said stop relay 206 remains energized. This relay does not fall back, it will be remembered, until after a sufficient interval of time has elapsed for the selector last operated to select a trunk.

It may occasionally happen that the sending equipment of the director catches up with the registering mechanism, and that just before stop relay 206, Fig. 3, falls back to permit the switching through operation, the calling subscriber again manipulates his calling device for another digit, thereby causing the next digit register, the digit register DR¹ for example, to be operated, which results in the switching through operation being delayed until the registered digit is sent out. If special arrangements were not provided, the

sending equipment might start so soon after the digit register DR¹ has moved off normal that, in case the calling device of the calling subscriber is slightly slow, the sending switch SEN might overtake the digit register being operated before the latter has completed its operation. This, of course, would result in the premature termination of the series of impulses being sent out. In order to take care of this situation, the relay 231 has been provided. This relay is slow acting and is maintained energized over conductor 227 and through armature 229 and its working contact after the director has "caught up" and before relay 206 has fallen back. Then, in case the digit register DR¹ does not move off normal until just before relay 206 lets go, the sending equipment is prevented from starting up for an interval owing to the fact that the circuit of sending relay 204 is maintained open at armature 232 by slow acting relay 231. By the time relay 231 falls back to start the next sending operation, the digit register DR¹, which is being operated, has advanced far enough to insure that it will not be overtaken by the sending switch SEN.

It may be desirable, in certain specific instances, to provide directors which do not switch through when they catch up but wait until the complete number has been recorded and sent out. This is not necessary or even desirable in most cases, but is often desirable when the directors are used in connection with a mixed service system, such as is found when part of the offices are manual and part of them automatic, such, for example, as the system assumed in the co-pending application of Nelson hereinbefore referred to. The chief reason, it may be pointed out, for having a director which does not switch through when it catches up is to permit the director to wait until the complete number has been called, and then add an extra digit in case the call is intended for a straight line manual office. This extra digit is useful only in causing the call indicators used in the manual office to switch through into display position, as is explained in the Nelson application referred to above. Accordingly, the director shown in the present application is arranged so that it may be used either to switch through when it catches up as described hereinbefore, or may be used to switch through only after the complete number has been received and sent out. Furthermore, the desired change may be made by merely operating the key K, Fig. 3, or restoring it to normal. With the key K at normal, the director switches through when it catches up as described hereinbefore. With the key K operated, however, conductor 227 is disconnected from the impulsing conductor 75 at spring 228, and is connected instead to stop relay 206. With conductor 227 disconnected from conductor 75, the director cannot, of course,

switch through until wiper 111 of the sequence switch S' reaches its last bank contact, at which time the complete number has been received and sent out. The reason for connecting conductor 227 to stop relay 206, it may be pointed out, is to prevent the advance of the sending equipment ahead of the registering equipment when the director catches up. In case the director catches up, the advance of sequence switch S', which occurs at the end of the transmission of a digit by the sending equipment, results in ground being placed upon the wiper of one of the digit registers, the digit register DR² for example, while that wiper is in its normal position. Ground is therefore extended to conductor 227, and with the key K operated, it is extended to stop relay 206. This occurs, it will be remembered, while stop relay 206 is still energized, and accordingly stop relay 206 remains energized until the digit register DR² has been moved from its normal position, and then, after an interval which is sufficiently long to insure that the sending switch SEN does not overtake the digit register DR², stop relay 206 falls back and again starts the sending switch.

It might possibly be well to point out at this time that, since the repeater R is interposed in the trunk line extending to the first selector, it is not necessary to provide repeaters on the outgoing trunks. Repeaters are ordinarily provided on these trunks in order to furnish a short path for the battery feed to the calling subscriber, as well as to avoid the necessity of a third conductor in the associated inter-office trunk, and also to repeat the impulses to the associated switch in the distant office. The repeater R performs all these functions, and therefore obviates the necessity of a separate repeater on each outgoing trunk. The applicants are aware that this idea is not broadly new, and that repeating mechanism has been combined with selector switches heretofore, the combination being known as a selector repeater. However, in the present case, a considerable saving of equipment is effected, owing to the fact that the same line and release and repeating relays are used in the repeater R, that would be required to be duplicated in case the outgoing trunks were each provided with a separate repeater.

What we claim is:

1. In a telephone system, a trunk, means for extending a calling line to said trunk, a call director, means for automatically connecting said director to said trunk responsive to said extension of the calling line, means in said director for registering the digits in the desired number as they are called, means for translating certain of said digits into a set of code digits, sending means in said director for retransmitting series of impulses over said trunk in accordance with the code digits and
- the untranslated digits to extend the connection to the called line, means for starting said sending means upon the registration of the last digit to be translated, and means for disconnecting the director and for restoring it to common use responsive to said sending means catching up with said registering means at any point in the sending operation. 70
2. In a telephone system, a trunk, means for extending a calling line to said trunk, a call director, means for automatically connecting said director to said trunk responsive to said extension of the calling line, means in said director for registering the digits in the desired number as they are called, means for translating certain of said digits into a set of code digits, sending means in said director for retransmitting series of impulses over said trunk in accordance with the code digits and the untranslated digits to extend the connection to the called line, means for starting said sending means upon the registration of the last digit to be translated, means for disconnecting the director and for restoring it to common use responsive to said sending means 75 80
3. In a telephone system, a trunk, means for extending a calling line to said trunk, a call director, means for automatically connecting said director to said trunk responsive to said extension of the calling line, means in said director for registering the digits in the desired number as they are called, means for translating certain of said digits into a set of code digits, sending means in said director for retransmitting series of impulses over said trunk in accordance with the code digits and the untranslated digits to extend the connection to the called line, means for starting said sending means upon the registration of the last digit to be translated, means for disconnecting the director and for restoring it to common use responsive to said sending means 85 90
4. In a telephone system, a trunk, a call director, means responsive to a call over said trunk for connecting said director therewith, a plurality of registers in said director, means for operating said registers in succession for registering the digits in a called number, sending means controllable by any one of said registers, means for placing the sending means 120 125 130

under the control of said registers in succession, and means for disconnecting said director from said trunk responsive to the placing of the sending means under the control of any unoperated one of said registers.

5. In a telephone system, a trunk line, means for connecting a calling line with said trunk line, a director, non-numerical switching mechanism responsive to the call for connecting the trunk line and said director, registers in said director responsive to impulses received over the calling line, sending mechanism in said director controlled by said registers, a train of switches for extending said

10 trunk line to a called line, a repeating relay in said trunk line initially controlled by said sending mechanism to operate a part of said train of switches, and means for placing said relay under the control of the calling line 20 to operate the remainder of said switches.

6. In a telephone system, a trunk line, means for connecting a calling line with said trunk line, a director associated with said trunk line, registers in said director controlled over the calling line and over said trunk line, a sender in the director controlled by said registers, a repeating relay in the trunk line controlled by said sender, and means for cutting out the director and for placing said repeating relay under the control of the calling line.

7. In a telephone system, a repeater including a line relay and a repeating relay, a director, registers in said director controlled by said line relay, a sender in said director controlled by said registers, a circuit over which the sender controls said repeating relay, and another circuit over which the line relay controls said repeating relay.

40 8. In a director, a series of registers each having a normal position, a sending switch, a stepping relay for said switch, a pulse circuit for said relay, a stop relay controlling said pulse circuit, said stop relay controlled over circuits including a bank of said sender and the banks of said registers, and another circuit for said stop relay including the normal position contacts in the banks of said registers but excluding the bank of said sender.

55 9. In a director, a series of registers, a sending switch, a stepping relay for said sender, a pulse circuit for said relay, a stop relay energized under the control of an operated register to open said pulse circuit, means for transferring the control of said stop relay to a second register, and a circuit controlled by the second register in its normal position for holding said stop relay energized.

60 10. In a director a series of registers, a sending switch, a stepping relay for said sender, a pulse circuit for said relay, a stop relay energized under the control of an oper-

ated register to open said pulse circuit, means 65 for transferring the control of said stop relay to a second register, a circuit controlled by the second register in its normal position for holding said stop relay energized, and means in the second register for breaking 70 said holding circuit responsive to the movement of said second register from its normal position.

11. In a telephone system, a group of trunk lines, a director, individual switches 75 associated with said trunk lines all having access to said director, means for causing the switch associated with a trunk line which has been taken for use to connect with said director and make the same busy to other 80 switches, means for releasing the operated switch to free the director, means for restoring any operated apparatus in the director to normal, auxiliary busying means in the director for rendering it busy to said other 85 switches prior to the initiation of the release of the operated switch, and means responsive to the complete restoration of the director for rendering said auxiliary means ineffective.

12. In a telephone system, a group of trunk lines, directors, switching mechanism for connecting a trunk line on which a call has been received with an idle director, means for busying the seized director, means for releasing the seized director and for restoring operated parts thereof to normal after it has been used to extend the call, and means in the said director for maintaining the busy condition continuously from the time before its 100 release is initiated until its restoration to normal is completed.

13. In a telephone system, a switching apparatus having a test conductor, means for seizing said apparatus and for completing a 105 guarding connection to said test conductor, means in said apparatus operative subsequent to said seizure to complete a second guarding connection to said test conductor, a relay winding included in said second connection 110 and shunted by said first connection, means for releasing said apparatus after it has been operated and for energizing said relay winding by opening said first connection, a second relay winding energized responsive to the energization of the first said winding, means for subsequently opening the second said connection, and contacts controlled by said second winding closed prior to the opening of 115 said second connection for establishing a third guarding connection to said test conductor and for maintaining it until said apparatus is restored to normal.

14. In a telephone system, a switching apparatus having a test conductor, means for seizing said apparatus and for completing a 125 guarding connection to said test conductor, means in said apparatus operative subsequent

- to said seizure to complete a second guarding connection to said test conductor, a relay winding included in said second connection and shunted by said first connection, means 5 for releasing said apparatus after it has been operated and for energizing said relay winding by opening said first connection, a second relay winding energized responsive to the energization of the first said winding, 10 means for subsequently opening the second said connection, and means responsive to the restoration to normal of said apparatus for opening said third guarding connection.
15. In a telephone system, a switching apparatus having a test conductor, means for seizing said apparatus and for completing a guarding connection to said test conductor, a guard relay in said apparatus having two windings, means in said apparatus for completing a second guarding connection to said test conductor through one winding of said guard relay, said one winding being shunted by the first said connection, means for releasing said apparatus after it has been operated 20 and for energizing said relay through said one winding by opening the first said connection, a restoring circuit for said apparatus, and contacts on said guard relay operated upon the energization thereof to complete the said 25 restoring circuit and to establish a third guarding connection to said test conductor, said restoring circuit including the second winding of said guard relay, whereby said guard relay remains operated after said second connection is opened to maintain the third guarding connection intact until the 30 restoring circuit is opened.
35. The combination, with a device for automatic telephone systems, of a test conductor upon which a guarding potential is placed while said device is in use, a release magnet for restoring said device, a relay, a circuit for energizing said relay responsive to the removal of potential from said conductor, and a self locking circuit for said relay including said magnet.
40. The combination, with a device for automatic telephone systems, of a test conductor upon which a guarding potential is placed while said device is in use, a release magnet for restoring said device, a relay directly connected to said conductor and energized responsive to the removal of potential from said conductor, and means controlled 45 by said relay for placing a guarding potential 55 on said conductor.
45. In a director, a test conductor upon which guarding potential is maintained while the director is in use, a relay energized over said conductor, a second relay short circuited by said guarding potential and energized in series with said first relay when the guarding potential is removed, a release magnet, a locking circuit for said second relay including said release magnet, and contacts on 50 said second relay for placing a guarding potential on said conductor.
50. In a telephone system, a register sender including registering apparatus for registering digits in telephone numbers, and including sending means for retransmitting the registered digits, means for taking said director for use, means for freeing said director after it has functioned, timing means in 55 said register sender for spacing apart the digits transmitted by the sending means, means responsive to the retransmission of the last registered digit for freeing said register sender after said timing means has functioned, means responsive in case another digit 60 is received after the last registered digit has been retransmitted and before the director is freed for delaying the freeing of the register sender until the newly-registered digit has been retransmitted, and additional timing 65 means for further delaying the starting of the sending means only in case the last registered digit has been retransmitted before the first part of the newly-registered digit has 70 been received.
65. In a telephone system, a register sender including means for registering a plurality of digits and for retransmitting series of impulses corresponding thereto, means for taking said register sender for use, means for starting the transmission of impulses before all the digits have been registered, and means 75 responsive to the retransmission of the last registered digit regardless of the number of digits registered for freeing said register 80 sender.
70. In witness whereof, I hereunto subscribe my name this eighth day of August A. D., 1923.
75. JOHN I. BELLAMY. 105
80. In witness whereof, I hereunto subscribe my name this 20th day of August A. D., 1923.
85. JOHN E. GARDNER.
